UNITED STATES PATENT OFFICE.

DUNCAN GRAY, OF ALEXANDRIA, ONTARIO, CANADA.

WHEY-MEASURING APPARATUS.

No. 918,667.

Specification of Letters Patent.

Patented April 20, 1909.

Application filed July 2, 1908. Serial No. 441,701.

To all whom it may concern:

Be it known that I, DUNCAN GRAY, of the town of Alexandria, in the county of Glengarry, Province of Ontario, Dominion of Canada, have invented certain new and useful Improvements in Whey-Measuring Apparatus, of which the following is a specification.

My invention relates to whey measuring apparatus.

The object of my invention is to provide an apparatus by means of which a given quantity of whey, or other liquid, may be run off from a tank, and when that quantity has been run off, the supply will be automatically stopped.

A further object is to provide an apparatus of the character described, which may be operated from the office, or other point removed from the vat containing the whey.

My invention consists of the construction, combination and arrangement of parts, as herein illustrated, described and claimed.

In the accompanying drawings, forming part of this application, I have illustrated one form of embodiment of my invention, in which drawings similar reference characters designate corresponding parts, and in which:

Figure 1 is a vertical section through a whey vat and connected parts; Fig. 2 is a plan view of the whey vat and connected parts; Fig. 3 is a vertical section through a closure or valve; Fig. 4 is an inverted plan view of a closure or valve; Fig. 5 is a fragmentary detail in horizontal section through a locking pawl; and, Fig. 6 is a fragmentary detail in side elevation of a portion of a locking rack.

Referring to the drawings, 1 designates a supporting member, on which is disposed a whey vat 2. A discharge pipe 3 has one end connected with the interior of the vat 2, and has its opposite end connected with an open ended tank 4, which is provided with a discharge faucet 5. To prevent use of the apparatus until desired, a globe valve 40 is provided located within a casing 41, the cover 42 of which may be locked in position. The discharge pipe 3 and the faucet 5 are each provided with a tubular closure 6, having a projecting flange 7 formed to receive a gasket 8 on its under face, so that a perfect closure is made by the weight of the whey pressing on the flange 7.

A rod or connecting member 9 has its lower end connected to the closure 6 for the

outlet pipe 3, and has the opposite end secured to the long end of a lever 10, which is pivoted as at 11, and has secured to its opposite end a flexible connecting member 12, to the lower end of the latter of which is secured the closure 6 for the faucet 5. The lever 10 is so pivoted that its inner end will normally close the closure 6 connected therewith, and the connecting members 9 and 12 are proportioned in length so that the pipe 3 and faucet 5 will be alternately closed.

Movably disposed in the tank 4 is a float 13, provided with an opening for the connecting member 12, so that the float is free to move vertically in the tank.

Loosely disposed through the outer end of the lever 10 is a rack 15, adapted to be engaged by a pawl 16, secured on a stem 17 and normally maintained in the path of movement of the rack as by means of a spring 18. The stem 17 is disposed through an opening 19 in the block 20, which is adjustably secured in the side members 21 forming the lever 10. When in the position shown in Fig. 1, the pawl 16 engages the rack so as to cause downward movement of the outer end of the lever. This opens the closure for the outlet pipe 3, and permits the whey to run into the tank 4. Loosely disposed through the lever 10, is a casing 22 engaging the rack 15, and connected therewith by means of transverse pins 23 passing through diagonal slots 24 in the rack, thus holding the rack so that it may be retracted into the casing 22 to release the lever and permit its inner end to descend and seat the closure 6 in the top of the outlet pipe 3. This retraction of the rack into the casing is caused by the float 13 rising under the action of the whey admitted to the tank 4 below the float. The faucet 5 being open, the whey will be drawn off from the tank 4, the float will descend gradually, and finally the rack will be released and will be again engaged by the pawl 16 when the casing is elevated, as hereinafter described.

A flexible member 25 has its lower end secured to the casing 22, and is disposed over a roller 26 carried by an arm 27 secured to the vat 2, and also serving as a pivotal support for the lever 10. The flexible member is then disposed over rollers 28, and around a winding member 29, which may be finally located in the office of the plant to which this apparatus is connected. A scale 30 is secured to the flexible member 25, and dis-

posed in guides 31 adjacent pointers 32, which will indicate in figures the height to which the casing is drawn, and the proportion of whey which will be admitted to the tank 4 when the rack 15 is elevated to any particular point. As above described, when this quantity of whey is admitted, the lever will be tripped, the closure will be seated on the outlet pipe 3, and when the whey has been run off from the tank 4 the apparatus may be reset.

In the operation of the invention, the inner end of the lever 10 being lowered and the float 13 being adjacent the bottom of the tank 4, and it being desired to deliver a predetermined quantity of whey from the vat 2, the winding member 29 is actuated to move the flexible member 25, so that the casing 22 and the rack 15 are actuated upward until the scale 30 indicates such quantity. On its upward movement the rack 15 is free to slide over the pawl 16. The quantity being ascertained by means of the scale 30, the teeth of the rack 15 engage the pawl 16 and the weight of the rack causes the lever 10 to be rocked on its pivotal support, elevating the closure 6 from the end of the outlet pipe 3, permitting the whey to run through the pipe 3 into the tank 4, and carrying with it the float 13, which is elevated until it strikes the bottom of the rack 15. The float then actuates the rack upward, and the inclined slots through which are disposed the pins 23 permit the rack 15 to be actuated upward and backward into the casing 22, so that the pawl 16 is released from the teeth of the rack, and the lever 10 is permitted to rock by its own weight on its pivotal support 11, and the closure 6 seats itself on the end of the pipe 3, thereby cutting off the supply of whey. The faucet 5 is opened by the closure 6 being elevated therefrom by the flexible member 12, which is connected to the outer end of the lever 10, and the quantity of whey in the tank 4 is permitted to run off, the rack 15 following the downward movement of the float 13. Then if a different quantity of whey is desired, the winding member is actuated for such different quantity.

What I claim as my invention is:

1. A measuring apparatus comprising a vat, a tank connected with the vat, pivoted controlling means arranged for governing the outlet from the tank and the vat, a rack loosely disposed through the governing means, means for elevating the rack, an engaging means carried by the governing means coöperating with the rack and a float movable in the tank and adapted to engage the end of the rack and disengage the same from the engaging means.

2. A measuring apparatus comprising a discharge pipe, a tank to which the pipe is connected provided with an outlet, closures

for the pipe and the tank outlet, a lever, means connecting the ends of the lever with the pipe and the outlet, a rack disposed through the lever and working into the tank, a pawl carried by the lever and arranged to engage the rack, means for carrying the rack to permit its retraction out of the path of movement of the pawl, and means for retracting the rack.

3. A measuring apparatus comprising a discharge pipe, a tank connected with the discharge pipe and provided with an outlet, closures for the pipe and the outlet, a lever connected with the closures, a casing slideable through the lever, a rack disposed in the casing and retractable therein, a pawl carried by the lever and arranged to engage the rack, means for elevating the casing to a predetermined point, and a float in the tank arranged to engage the lower end of the rack to retract the same.

4. A measuring apparatus comprising a discharge pipe, a tank connected with the discharge pipe and provided with an outlet, a pivoted lever, connecting members carried by the lever, closures carried by the connecting members and arranged over the outlet and the discharge pipe, a casing loosely disposed through the lever, a rack slidably disposed in the casing and provided with diagonal slots, pins disposed through the casing and the slots, a pawl carried by the lever and arranged to engage the rack, means for elevating the casing, and means in the tank for engaging the rack to release it from the pawl.

5. A measuring apparatus comprising a vat, a tank; a pipe connecting the tank and the vat, an outlet pipe for the tank, a lever pivoted above the tank comprising side members, a block adjustably held between the side members, a pawl having a stem adjustably disposed through the block, a spring arranged on the stem, a rack disposed through the lever, a casing arranged to receive the rack, means for elevating the casing, means for engaging the bottom of the rack when a predetermined quantity of matter is admitted to the tank, closures for the outlet pipe of the tank and the connecting pipe, and means for connecting the closures to the opposite ends of the lever.

6. A measuring apparatus comprising a vat, a tank connected therewith, closures for the tank and the vat, a gravity operated trip for governing the position of the closures, a flexible member connected to the trip, a winding member connected to the flexible member, and indicating means coöperating with the flexible member to indicate the position of the trip a weight having means releasably connecting the same with the trip and being adapted to maintain the trip in position with one closure open and the other closure closed, and a float in the tank adapt-

ed, when it reaches a determined position, to disengage the weight from the trip.

7. A measuring apparatus including a vat, a tank connected therewith, conducting means between the vat and tank, a valve controlling the conducting means, gravity-operated means for closing the valve, a weight having means for releasably connecting the same with the means for actuating the valve and being adapted to maintain the

valve in open position and a float in the tank adapted to release the weight when it reaches a given height.

In witness whereof I have hereunto set my hand in the presence of two witnesses.

DUNCAN GRAY.
